UNITED STATES PATENT OFFICE.

CECIL ARTHUR CHURCH, OF PETERBORO, ONTARIO, CANADA.

EXTENSION FOR ELECTRIC-LIGHT SOCKETS.

Application filed August 27, 1924. Serial No. 734,514.

To all whom it may concern:

Be it known that I, CECIL ARTHUR CHURCH, a subject of the King of Great Britain, resident of the city of Peterboro, in the 5 Province of Ontario, in the Dominion of Canada, having invented certain new and useful Improvements in Extensions for Electric-Light Sockets, do hereby declare that the following is a full, clear, and exact 10 description of the same.

The invention relates to improvements in extensions for electric light sockets as described in the present specification and shown in the accompanying drawings which 15 form a part of the same.

The object of the invention is to provide a connecting device, more particularly for domestic use, whereby push plugs of cords extending from electrical appliances may be 20 readily attached to an ordinary light socket without having to remove its shade in order to comfortably effect such connection. With this object primarily in view, a further purpose of the invention is to provide a device 25 of this class which will be economical in construction and efficient in its use.

Whereas in the connecting of modern electrical appliances with an ordinary light socket, on account of the small space available 30 within the light shade not conveniently permitting of the insertion of a person's hand for the purpose of screwing the connection in place in the socket, the present invention consists of an elongated insulative 35 member of sufficient length that same may be connected without either removal of the light shade or cramping of the hand of the party effecting such connection. The said insulative member bears a threaded end for 40 the purpose of screwing into the light socket, its other end being formed receptive to contacts of a push plug; electrical connections existing, of course, between the two ends for the transmission of current from the socket 45 to the plug.

Referring to the drawings, Figure 1 is a view illustrating the invention attached to a socket of an electric light fixture possessing a shade, the socket and its shade being 50 shown in dot and dash lines.

Figure 2 is a longitudinal section of the extension.

Figure 3 is a transverse section thereof taken on the line 2-2 of Figure 1.

Figure 4 is a sectional view of the push plug depicted in Figure 1.

Like numerals of reference indicate corresponding parts throughout each figure of the drawings.

In the drawings, the reference numeral 1 60 denotes the conventional socket shown in Figure 1 of the drawings, and 2 the shade appended to same, which, of course, may be of any shape or design.

The extension itself comprises companion 65 sections 3 of a semi-circular cross section, which together form a round shaped body 4 of a length sufficient to project beyond the mouth of the average electric light shade in order to obviate manufacturing in a variety 70 of lengths.

Each section 3 is provided with a corrugated periphery 5 terminating short of its ends for the purpose of affording a secure 75 manual grip upon the body 4. Moreover, one end of each section is flared annularly, as at 6, terminating in an abrupt face 7, while the other end is formed with a projection 8.

The abutting face 9 of each section, discernible in Figure 3, is provided with a pair 80 of parallel longitudinally extending grooves 10, which, when the sections are brought together, register to produce channels of rectangular cross sections as shown. These 85 channels at the abrupt end-face 7 are enlarged and the openings formed thereby are restricted by integral projections 11.

One of the channels at the other end of the body 4 emerges into a lateral opening 90 12, the other passing therethrough in close proximity to the projection 8.

13 and 14 are a pair of electrodes preferably constructed of copper ribbon; an end of the electrode 13 being bent back upon itself as at 15 for a distance slightly less than the length of the openings at the flared ends 6 of the body-forming sections and extended to the projection 8 at the other end. The other electrode 14 is provided with a similarly bent end 16 and extends to the lateral opening 12, thus providing a pair 95 of resilient terminals receptive to a push plug.

These electrodes are inlaid in their correct 105 positions between the sections 3 which are then affixed by passing bolts 17 through apertures and securing same therein with nuts threaded thereupon.

Upon the complementary sections being 110 assembled to form the body 4, a metallic ring 18 threaded to engage a light socket is

secured over the end bearing the projection 8 and thereupon connected to the electrode 14.

19 is the push plug provided with prongs 5 20 spaced relative to the openings in the channels in the grooves 10 in which they necessarily have to fit for engagement with the terminals 15 and 16 of the electrodes. A cord 21 of any suitable length extends to, 10 and is electrically connected with, any appliance with which connection is desired.

What I claim is:—

In a device of the class described, a pair of insulative sections forming a body, each 15 section having a linear groove extending

along its contiguous face, said grooves registering one with the other in order to constitute a channel, one end of which is enlarged and open, an electrode inlaid in the channel with the portion within its enlargement bent back upon itself, thus forming a resilient contact engageable by a prong; and a constrictive projection positioned in advance of the return bend of the electrode in order to effect its obstruction and also to render only the outer face of the contact accessible to the prong. 20 25

Signed at Peterboro, Canada, this 7th day of June 1924.

CECIL ARTHUR CHURCH.
